UNITED STATES PATENT OFFICE

WILLIAM G. KELLEWEAY, OF NEW YORK, N. Y.

PARTITION STRIP FOR COMPOSITION FLOORING

Application filed January 31, 1929. Serial No. 336,487.

This invention relates to partition strips for composition flooring, such as terrazzo and the like, and aims to provide a strip that is formed with positive means for anchoring it into the cement bed, which is usually laid as a foundation for the composition flooring, and to absolutely prevent the strip from working loose.

An object of the invention is to provide the strip at its opposite sides with pairs of longitudinally opposed struck out wings to provide cement receiving pockets between and in back of the wings. The cement hardening between and in back of the wings forms lugs in the hard cement disposed in said pockets so as to absolutely prevent the strip from moving in any direction. Furthermore, the angle of the wings is such as to create equal pressure receiving surfaces at opposite sides 20 of the strip resulting in a positive anchoring of the strip within the cement.

An additional object is to provide anchorage means that will absolutely not necessitate the forcing of the anchor entirely into the cement bed. The structure is such that even though the lower portion only of the various anchors is forced into the cement, a positive anchor will be had until the terrazzo is laid.

A further and additional object is to provide a partition strip of this character, wherein the anchorage means is an integral part thereof, and that can be struck from the strip by not more than two mechanical operations, with the result that the complete strip can be manufactured at nominal cost.

With the foregoing and other objects in view as the nature of the invention will be better understood from the following specification in accompaniment with the drawing, wherein like reference characters indicate corresponding parts throughout the several views, and wherein:

Figure 1 is a fragmentary perspective and section through a floor structure before the floor composition is disposed upon the cement bed, and within which bed has been arranged the partition strips constructed in accordance with the present invention.

Figure 2 is a fragmentary section through a complete floor and my partition strip.

Figure 3 is a fragmentary side elevation of the improved strip, and

Figure 4 is a longitudinal section taken substantially upon the broken line 4—4 of Figure 3.

Now, having particular reference to the drawing, the strip which is of brass, copper or other suitable material is designated 5 and obviously, it is of any desired length, width and thickness, as well as being of any 60 suitable design. The various anchors are formed at predetermined spaced points throughout the length of the strip, and are alternately at opposite sides of the strip as in Figures 1, 3 and 4. Furthermore, these 65 anchors are beneath the center line of the strip, and in each instance, they are produced by spaced pairs of relatively wide V-shaped incisions 6—6, the apices of which are directly opposed to each other, and are parallel 70 with the longitudinal axis of the strip, see Figure 3. The upper ends of these incisions are slightly beneath the center line of the strip, while the lower ends thereof are likewise spaced from the lower edge of the strip. After making the incisions in the strip, the material between the complementary ones of the pairs is forced directly outwardly to provide opposed relatively wide V-shaped wings 7—7. The formation of these wings will also 80 provide similarly shaped slots 8—8 in the strip, so as to permit the cement to pass therethrough when the lower edge of the strip is embedded in the cement A, as in Figure 2. The opposed wings 7—7 will cooperate with 85 the strip 5 for providing a pocket 9 within the confines of the opposed wings for the reception of the cement as also disclosed in Figure 2. The ends of the wings as well as the edges of the slots will be firmly bound to 90 the cement to prevent movement of the strip therein. The inclined faces and edges of the wings will also be encountered by the cement as to provide further means to prevent slip- 95 page of the strip. Even though the lower half of the strip is not entirely embedded in the cement, as shown in Figure 2, a sufficient amount of the cement will pass through the slots and into the pockets as well as encounter 100

the angled wings to prevent movement of the strip.

In view of the foregoing description when considered in conjunction with the accompanying drawing, it will be apparent to those skilled in the art, that I have provided a novel, simple and useful partition strip for composition flooring, that is well adapted for all of the purposes designated, and even though I have herein shown and described the strip as being composed of anchors constructed in a particular manner, and of a particular shape, it is of course to be understood that I do not desire to be so limited, as certain changes may be made without departing from the spirit and scope of the appended claims.

Having thus described my invention, what I claim as new and desire to secure by Letters Patent, is:

- 20 1. In a partition strip for composition flooring, pairs of substantially V-shaped opposed wings struck from the strip to provide cement receiving pockets in the strip as well as slots through which the cement will pass when the strip is forced into the composition flooring plastic material base, said wings being formed beneath the center line of the strip and having their apices in close spaced relation.
- 25 2. In a partition strip for composition flooring, pairs of substantially V-shaped opposed wings struck from the strip to provide cement receiving pockets in the strip as well as slots through which the cement will pass when the strip is forced into the composition flooring plastic material base, said wings being formed beneath the center line of the strip and having their apices in close spaced relation, and in a plane parallel with the longitudinal axis of the strip.
- 30 3. In a partition strip for composition flooring, a plurality of substantially V-shaped wings struck from the strip at spaced points throughout the length thereof, said wings being connected at their opposite ends to the strip and forming when struck from the strip a plurality of cement passage slots within the strip.
- 35 40 45 50 In testimony whereof I affix my signature.
WILLIAM G. KELLEWEAY.
